UNITED STATES PATENT OFFICE.

WILLIAM H. MAHAN, OF PEORIA, ILLINOIS.

CONDUCTOR'S EQUIPMENT CASE.

Application filed December 17, 1922. Serial No. 681,197.

To all whom it may concern:

Be it known that WILLIAM H. MAHAN, a citizen of the United States of America, residing at Peoria, in the county of Peoria 5 and State of Illinois, has invented certain new and useful Improvements in Conductors' Equipment Cases, of which the following is a specification.

My invention relates to conductors' equipment cases.

The object of my invention is in the provision of a simple case having portions therein adapted to support in an operative position the money register carried by conductors in street cars and other passenger carrying vehicles.

Another object of my invention is in the provision of a receptacle adapted not only to house in an operative position the formal 20 money changer, but also to house other exchange mediums as well as providing a reserve space for extra change.

A further object of my invention is in the provision of a conductors' equipment case 25 adapted to be utilized not only as a housing member for the formal money registered, but also adapted to provide a safe means for transporting other necessary equipment.

Other objects of my invention will appear 30 in the following specification taken in connection with the annexed drawings in which—

Fig. 1—is a side perspective view of my 35 case, the lid being opened and the money register in place.

Fig. 2—is a view of the case closed.

Fig. 3—is a perspective of the case with 40 the money register or change maker removed and the rear compartment opened; and

Fig. 4—is a sectional view taken on the line 4—4 of Fig. 3, the money register having been removed.

Referring to the drawings, I have shown 45 a stamped metal box generally referred to as 10, but made up of the main box 11, and the lid or face portion 12 hinged at the bottom as at 13 thereto. The box itself is 50 no more than a stamped metal container, and has a formal handle 14 and means for securing the top and base portions together securely at 15, a formal padlock being shown at 16. Within the box as shown in Fig.

3 is mounted a metal sheet or wall 17 pivotally related at its lower end to the box housing member as at 18, this pivotal connection to the main housing portion being peculiar in that the supporting body or wall 17 has a double hinge or crank operating 60 movement, due to the angular fashioning of the rod which provides the pivotal mounting due to the engagement of its projecting ends with the sides of the box. It may be seen in Fig. 4 that with the upper end of 65 the wall 17 in a disengaged position, a crank movement thereof will either place it in a position near the front of the box or in an inward position, a substantial distance within the box. As said before, this crank movement of the wall can only be accomplished with the upper end thereof released from the upper side of the box; however, means is provided for holding the above mentioned 70 wall either in its front or rearward position 75 in a tensioned catch member 20 adapted to be engaged by a spring-pressed lug 21 on the wall.

The wall 17 is adapted to receive the conventional money register on its front face 80 by merely having the register of well known construction hooked over the upper edges thereof, as at 22, and held in a firm position thereon by means of the clasps 23 mounted on the sheet 17.

Within the box and adjacent the inner wall thereof are shown spring-tensioned members 24 adapted to receive the reserve cash supply of the conductor, this reverse supply usually being contained in the cylindrical money rolls 25 here shown.

Chains 26 attached at 27 and 28 to the box and cover respectively, prohibit movement of the lid 12 further than a right-angular position with relation to the box. 95 The reason for the above is that it is desirable that the lid 12 act as a catch member for the money register.

In Figure 1 the normal operative position of my box and the formal money register 100 are shown. It may be stated that this box or case may be hung in a convenient position with relation to the conductor, the lid lowered to the position shown in Fig. 1, and the money register drawn to the position shown in said figure, due to the crank movement of the wall 17; in other words, drawn 105 from a position somewhat within the box

to the outer position shown in Fig. 1 where the register is adapted to be more easily operated by the conductor.

In the position shown in Fig. 1 the conductor can place his transfers or other equipment in the lowered lid and make change by merely pressing the formal key members of the register, either catching the change in his hand or picking it out of the lid which 10 acts as a catch member. In case a reserve supply of change is needed, he merely releases the catch member, permitting the wall 17 to fall forward with the money register, and withdrawing from the rear compartment other money rolls with which he again 15 fills the register, returning the wall of course to its operative position, that is, engaging the catch portion 20.

When the day's run has been made and it 20 is desirable that the receipts be collected, the conductor merely releases the clasp 21, permitting the wall 17 to fall forward in a position that it may be again operative by a crank movement to return it to its innermost position with the box, carrying with it 25 of course the money register. This inner

movement of the wall is necessary that the lid may be clasped to the main box portion and the padlock secured thereon.

What I claim is:—

1. In a device of the class described, in combination a container comprising hinged sections adapted to open at right angles to each other, a wall member having a crank operated, pivotal relation to one of said hinged portions, an optional catch means adapted to retain the upper end of said wall, a money register, and means for fastening said money register upon said wall member. 35

2. In a device of the class described, in combination a container comprising a box portion and a hinged lid adapted to open at a right-angular relation thereto, a wall member within said box, a money register adapted to be attached to said wall member and means for moving said wall member in a crank-operated manner in order to advance and return said money register within said box member. 40 45

In testimony whereof I affix my signature.

WILLIAM H. MAHAN.
